Attorney

UNITED STATES PATENT OFFICE.

CLAUDE DAUGHERTY, OF BUTLER, MISSOURI, ASSIGNOR OF ONE-FOURTH TO LEE A. WOODS AND ONE-FOURTH TO ELMER D. CUTLER, OF SMITHVILLE, MISSOURI.

DRAFT APPLIANCE.

Application filed August 10, 1925. Serial No. 49,371.

The present invention relates to a draft appliance and has for its principal object to provide a modification of the invention disclosed in my copending application Serial Number 39,763, filed June 26, 1925, also relates to a draft appliance. The principal object of the invention is to provide a device of this nature wherein the same is applicable to what is known as a stiff hound wagon.

In the drawing:—

Figure 1 is a top plan view of the improved structure.

Figure 2 is a side elevation thereof.

Figure 3 is a front elevation thereof showing the main tongue in transverse section.

Referring to the drawing in detail it will be seen that the numerals 5 designate the two hounds rigidly attached to the axle 6 in the usual manner. A metallic frame 7 is positioned between the hounds 5 in front of the axle 6 and carries the stub tongue 8 on the center line of the wagon and having on that part nearest to the front axle 6 a stop 9 which is engageable with the under surfaces of the hounds 5 thereby placing the weight of the tongues on the hounds and limiting the downward movement of said tongue. This frame is attached to the hounds by means of a queen bolt 10 which passes through the hounds, the frame, and the stub tongue, the lateral position of these parts being maintained by spacing sleeves 11 on the queen bolt. Outside of one of the hounds is placed a frame 12 through which and beyond which extends the queen bolt 10. A main tongue 13 is hinged on the queen bolt adjacent the frame 12 so as to be positioned in parallelism with the center line of the wagon or stub tongue 8. A brace 14 is attached to the axle 6 as at 15 and to the queen bolt 10. A brace arm 16 is attached to the tongue 13 forwardly of the queen bolt and is pivoted to the queen bolt adjacent the hounds 5 farther from the tongue 13. The tongue is allowed to swing

vertically up and down and at the same time tends to transmit all side motion to the hounds and through them to the front 50 axle. The brace 16 is curved as is indicated to advantage in Figures 2 and 3 so that the tongue 13 may be swung upwardly from the position shown in Figure 2. The triple tree, not shown, is attached to the stub 55 tongue at a point near its front end in the conventional manner.

It is thought that the construction, utility, operation, and advantages of the invention will now be clearly understood but it 60 is desired to point out that numerous changes in the details of construction may be resorted to without departing from the spirit or scope of the invention as hereinafter claimed or sacrificing any of its ad- 65 vantages.

Having thus described my invention what I claim is:—

In a draft appliance wherein there is provided a pair of hounds rigidly mounted on 70 the axle of a vehicle, a queen bolt passing transversely through the hounds forwardly of the axle, a frame pivoted on said queen bolt between the hounds forwardly of the axle, a stop on said frame engageable with 75 the hounds adjacent the axle, and a stub tongue rigidly attached to the frame between the hounds; said appliance including a second frame mounted on the outside of one of said hounds, said queen bolt passing through the second frame and therebeyond, a main tongue hinged to the queen bolt adjacent the second frame so as to swing in a plane in parallelism with the plane in which the stub tongue swings, and 80 a curved brace fixed at one end to the main tongue forwardly of the queen bolt and pivotally engaged at its outer end with the queen bolt adjacent the hound which is farthest from the main tongue. 85

In testimony whereof I affix my signature.

CLAUDE DAUGHERTY.
